[57] CLAIM

The ornamental design for paper product, as shown and described.

DESCRIPTION

FIG. 1 is a top front perspective view of a paper product, showing our new ornamental design.

FIG. 2 is a top plan view of the paper product shown in FIG. 1, the opposite (bottom) side view being a mirror image thereof.

FIG. 3 is a frontal view of the paper product shown in FIGS. 1 and 2, the opposite (rear) view being a mirror image thereof; and,

FIG. 4 is a side elevational view of the paper product shown in FIGS. 1, 2 and 3, the opposite side elevational view being a mirror image thereof.

It is to be understood that the design pattern shown in FIGS. 1-4 continues uniformly throughout the length and width of the paper product; the paper product is shown broken away to indicate that the paper product has indeterminate length and width. The broken lines are for illustrative purposes only and form no part of the claimed design.
